US00D643028S

(12) **United States Design Patent**
Richardson et al.

(10) **Patent No.:** **US D643,028 S**
(45) **Date of Patent:** **** Aug. 9, 2011**

(54) **CASE**

(75) Inventors: **Curtis R. Richardson**, Fort Collins, CO (US); **Jamie L. Johnson**, Fort Collins, CO (US); **John H. Loudenslager**, Phoenix, AZ (US); **Stephen Willes**, Fort Collins, CO (US); **Alan V. Morine**, Fort Collins, CO (US); **Adam L. Wibby**, Fort Collins, CO (US)

(73) Assignee: **Otter Products, LLC**, Fort Collins, CO (US)

(**) Term: **14 Years**

(21) Appl. No.: **29/354,590**

(22) Filed: **Jan. 26, 2010**

(51) LOC (9) Cl. **14-03**

(52) U.S. Cl. **D14/250**

(58) Field of Classification Search D14/138, D14/156, 248, 250, 251, 252, 253, 469; D3/215, D3/218, 219, 226, 269; 361/679.56; 455/575.8; 379/455

See application file for complete search history.

Primary Examiner — Susan Bennett Hattan
Assistant Examiner — Barbara Lohr

(57) **CLAIM**

The ornamental design for a case, as shown and described.

DESCRIPTION

FIG. 1 is an isometric view of a case showing our new design.

FIG. 2 is a front view thereof.

FIG. 3 is a rear view thereof.

FIG. 4 is a left side view thereof.

FIG. 5 is a right side view thereof.

FIG. 6 is a top view thereof; and,

FIG. 7 is a bottom view thereof.

The broken line portions of the disclosure are for illustrative purposes only and form no part of the claimed design.

1 Claim, 7 Drawing Sheets# US D643,028 S
